(57) **CLAIM**

The ornamental design for fish wings, as shown and described.

DESCRIPTION

FIG. 1 is a top isometric view from the back of the fish wings.

FIG. 2 is a top view of the fish wings.

FIG. 3 is a bottom view of the fish wings.

FIG. 4 is a back view of the fish wings.

FIG. 5 is a front view of the fish wings.

FIG. 6 is a right side view of the fish wings.

FIG. 7 is a left side view of the fish wings; and,

FIG. 8 is a top view of the fish wings with a bait fish and a transparent band illustrated in dotted lines.

The dotted lines referenced above show an example application with a bait fish and a transparent band but are not part of the fish wings.
